CLAIM

The ornamental design for an oil burner primary control, as shown and described.

DESCRIPTION

FIG. 1 is a front, top and right-side perspective view of an oil burner primary control;

FIG. 2 is a front, bottom perspective view thereof;

FIG. 3 is a back, top and left perspective view thereof;

FIG. 4 is a front elevation view thereof;

FIG. 5 is rear elevation view thereof;

FIG. 6 is a right-side elevation view thereof;

FIG. 7 is a left-side elevation view thereof;

FIG. 8 is top plan view thereof; and,

FIG. 9 is a bottom plan view thereof.

The broken lines depict portions of the oil burner primary control that do not form part of the claim.

1 Claim, 9 Drawing Sheets
